UNITED STATES PATENT OFFICE.

GEORGE W. NICHOLS, OF CLINTON, ASSIGNOR OF ONE-HALF TO THE NOVELTY IRON WORKS, OF DUBUQUE, IOWA.

AIR-CUSHION COMPRESSION-CYLINDER FOR GANG-SAWS.

SPECIFICATION forming part of Letters Patent No. 241,701, dated May 17, 1881.

Application filed October 4, 1880. (No model.)

To all whom it may concern:

Be it known that I, GEORGE W. NICHOLS, a citizen of the United States, residing at Clinton, in the county of Clinton and State of Iowa, have invented a new and useful Improvement in the Combination of Air-Cushion Compression-Cylinders with Gang-Saw Mills, of which the following is a specification.

My invention consists in the combination of air-compression cylinders for operating the pressure-rollers of gang-saws with an air-compression cylinder, which is combined with the gang-sash by means of suitable pipes, as hereinafter fully described.

In the accompanying drawings, which make a part of this specification, Figure 1 is a side elevation of a gang of saws and parts connected therewith, one of the side frames, A, being removed. Fig. 2 is a front elevation of the same. Fig. 3 is a section, on an enlarged scale, through the central vertical plane of the air-cushion compression-cylinders g and l l. Fig. 4, Sheet No. 2, is a side elevation of the saws and parts in connection, with one of the side frames, A, removed, and the compression-cylinders l l omitted, the pressure-rollers n n being operated by gearing in the usual manner. Fig. 5 is a front elevation of the same.

Like letters of reference in all the figures indicate the same parts.

A A, Figs. 1 and 2, represent side permanent frames, between which the gang-saws B have their up and down movements. These saws are connected with the reciprocating sash b in the usual manner. The sash has its vertical movements in the slides c c, connected with the frames A A, and is operated by means of the pitman d and crank e.

For the purpose of assisting in checking and reversing the movements of the sash b, and preventing the jars incidental to its quick reciprocating movements, and consequently relieving the crank-shaft of a large amount of strain, I combine with the sash an air-cushion compression-cylinder, g, which is permanently connected with the cap-plate A' of the frames A A. The cylinder is provided with a piston, h, having a rod, f, connected with the upper end of the sash, in the middle thereof, and has any suitable number of openings, i, through

its wall for the admission of air into each end as the opposite end of the piston passes the openings, thereby forming an air-compression cushion for the piston at each end of its stroke. As the air is compressed in each end of the cylinder g, it is thereby forced through the pipes k k into the air-cushion compression-cylinders l l, (as more clearly illustrated in the enlarged sectional view, Fig. 3,) and, acting on the pistons m m, forces the rollers n n connected with the lower ends of the piston-rods f' f' down upon the timber to be sawed or raises them up, as may be desired. The action of the pistons is controlled by means of the valves o o, operated by the levers p p. The pressure is controlled by means of suitable safety-valves q q. The escape of the air is prevented by the check-valves r r.

The compression-cylinders l l, for operating the pressure-rollers of gang-saw mills, form the subject of another application of the same date as the present application. Therefore a further description is deemed unnecessary in this place.

When it is desired to dispense with the compression-cylinders l l, in place thereof I operate the pressure-rollers in the usual manner by screws and gearing, as seen in Figs. 4 and 5, Sheet No. 2. As there is nothing new in this arrangement a particular description is deemed unnecessary.

I have represented the compression-cylinder g in connection with a gang-saw sash moving in fixed slides. It may, however, be connected with the frame of oscillating gang-saws, as set forth in another application of corresponding date to this.

I claim as my invention—

The combination, with the air-cushion compression-cylinder g, having inlets i and piston h, the air-cushion compression-cylinders l l, having pistons m m and rods f f, the connection between the said cylinders g and l l being made by means of the pipes k k, having valves o q r, for giving a yielding force to the rollers n n, substantially as described.

GEORGE W. NICHOLS.
